UNITED STATES PATENT OFFICE

123,553

DESIGN FOR A HASSOCK

Martin Leeb, Chicago, Ill.

Application September 26, 1940, Serial No. 95,419

Term of patent 3½ years

To all whom it may concern:

Be it known that I, Martin Leeb, a citizen of the United States, residing at Chicago, in the county of Cook and State of Illinois, have invented a new, original, and ornamental Design for a Hassock, of which the following is a specification, reference being had to the accompanying drawing, forming a part thereof, in which:

Figure 1 is a top plan view; Figure 2, a side elevational view; and Figure 3, an end elevational view of a hassock showing my new design.

I claim:

The ornamental design for a hassock, as shown.

MARTIN LEEB.
